UNITED STATES PATENT OFFICE.

JOHN W. SHIMEK, OF LAKEWOOD, OHIO, ASSIGNOR TO THE R. C. PRODUCTS COMPANY,
OF CLEVELAND, OHIO, A CORPORATION OF OHIO.

RETAINING-WALL STRUCTURE.

Application filed December 13, 1926. Serial No. 154,320.

The invention relates to retaining walls and other structures, particularly wall structures made of concrete beams set at substantially right angles to each other, such as are disclosed in the copending application of Evers and Shimek, Serial No. 20,037, filed April 2, 1925.

Such constructions are often subjected to excessive stresses and vibrations by which they are distorted, weakened or broken.

It is the object of this invention to strengthen such structures in a simple and effective way, and the invention consists in means hereinafter described and particularly pointed out in the appended claims.

In the annexed drawings:

Figure 1 is a front elevation, partly in section, of a portion of a complete wall of the character indicated, showing my invention embodied therein.

Fig. 2 is a sectional plan view taken on line II—II of Fig. 1.

Fig. 3 is a vertical cross-section showing the wedges of my invention incorporated therein taken on line III—III of Fig. 1.

Figs. 4, 5 and 6 show one of the wedge blocks of my invention, Fig. 4 showing the small end of the wedge, Fig. 5 showing a side elevation thereof, and Fig. 6 showing the large end thereof.

Fig. 7 is a side elevation of a modified form of the invention showing a wedge block formed integral with the header.

Fig. 8 is an end elevation of Fig. 7.

Fig. 9 is a fragmentary vertical section similar to Fig. 3, on line IX—IX of Fig. 10, showing the modified form of header, and

Fig. 10 is a cross-section taken on line X—X of Fig. 9.

Referring to the drawings in detail in which the same reference number is used throughout to designate the same part and particularly to Figs. 1 to 6 inclusive, the wall is formed of stretchers 1 and headers 2, the stretchers lying parallel with the front face of the wall and the headers substantially at right angles thereto, and forming anchoring members. The stretchers are of I-beam form, having opposed grooves 3, 4, while the headers 2 are provided with integral lugs or projections 5, 6, which engage in the recesses 3, 4 of the stretchers, all as disclosed in the prior application referred to.

Such a concrete crib structure is built from the bottom upward, and in order to make a

good wall structure it is necessary to tamp earth or other material about each horizontal set of stretchers and headers as they are put in place. It often occurs that this work is inefficiently performed or that frozen earth is used as a filler, with the result that the earth settles or shrinks, sometimes, to the extent of twenty-five or thirty per cent, leaving the concrete work insufficiently supported. In such case the structure may be distorted, weakened or broken under the constant thrust of heavy loads or from vibrations resulting from passing trains or trucks. In accordance with this invention the concrete structure is strengthened in an effective but very simple way at the points which are required to withstand the greatest stress.

It is impracticable to make concrete beams of the type disclosed herein with exactness, in consequence of which the vertical distance between adjacent headers varies. For example, while it is intended to so construct the beams that when assembled, adjacent faces of the headers will be eight inches apart, this distance may vary as much as a quarter of an inch.

In order to strengthen the structure at selected points, I insert concrete blocks between the headers at such points, so designed that a single block of certain form and dimensions, when used with a like block, will effectively fill the space between adjacent headers at any desired point, no matter what the variation in distance between them may be, at the same time permitting complete engagement between the stretchers and headers at their interlocking points. This result is accomplished by providing a filler block 7, Figures 4, 5 and 6, in the form of a wedge, having opposite faces 8 and 9, of which the face 9 is inclined from the plane of the face 8, the latter being adapted to engage a face of a header 2 and the inclined face 9 engaging the inclined face of another like block whose opposite face 8 is adapted to engage the adjacent face of another header 2 vertically adjacently aligned with the first-mentioned header. The angular relation between the faces 8 and 9 of the block should be the minimum angle which will enable a pair of blocks to completely fill the space between the faces of the adjacent headers while affording sufficient engagement between two faces 9 to take the thrust imposed upon the blocks and a frictional resistance

to movement which will prevent the blocks from working out or away from each other by vibrations to which the structure may be subjected. In practice it has been found 5 that an angle of 7° to 10° between the faces 8 and 9 meets all the required conditions. If the concrete beams could be made with less variation than that above indicated this angle would be reduced, as it is the extent 10 of such variations that determines the maximum angle. It will be obvious that the end faces of a pair of blocks will be in alinement or out of alinement according to the variations in distance between adjacent faces of 15 the headers, three different relations between the blocks being illustrated in Figs. 1, and 10, 11 and 12, indicating respectively, a distance between faces less than normal, normal, and greater than normal.

20. Substantially the same result may be accomplished by making the blocks 7 integral with the headers. Such a construction is shown in Figs. 7 to 10 inclusive, in which 13 designates such a block. In erecting a 25 structure composed of headers having integral blocks, a lug 6 of a header is placed in a groove 3 of a stretcher and moved laterally until the inclined face 14 of the block is in firm contact with the inclined face of an adjacent block. Where the blocks are thus 30 formed integral with the headers, the headers will be disaligned in accordance with the variations in dimensions of the headers and stretchers at their interlocking points as 35 above explained. This form is not as flexible as the form shown in Figs. 1 to 6 as the reinforcement must be confined to such points in the structure as may seem most desirable at the time the beams are made, while the 40 blocks 7 may be furnished in quantities at the building site, to be used in accordance with the demands of the particular environment.

45. From the above description it will be apparent that my invention constitutes a decided improvement in the art as it provides a very simple and practical means of remedying certain deficiencies in present structures, and materially extends the utility of 50 cribbed concrete structures, particularly in situations such as illustrated and described herein, the vertical series of blocks adjacent

to the interlocking parts of the beams in the front of the wall as shown in Fig. 3, for example, forming an additional column 55 of concrete, or a counterfort, to resist the crushing effect of the loads placed upon it.

What I claim is:

1. A crib retaining wall structure comprising a plurality of horizontal series of interlocked stretchers and headers in which the distances between the opposed faces of the respective pairs of adjacent vertically-aligned headers vary, and cooperating reversely arranged wedge blocks interposed 65 between adjacent headers.

2. A crib retaining wall structure comprising a plurality of horizontal series of interlocking stretchers and headers in which the distances between the opposed faces of 70 the respective pairs of adjacent vertically-aligned headers vary, and cooperating reversely arranged wedge blocks interposed between adjacent headers, at points adjacent to the inside face of the stretchers to 75 form a counterfort.

3. The construction specified in claim 1 in which the inclined faces of the wedge blocks are set at an angle of approximately 10°. 80

4. A crib retaining wall structure comprising a plurality of horizontal series of longitudinal stretchers, a plurality of horizontal series of alternate transverse headers interlocked therewith, the distances between 85 the opposed faces of the respective pairs of adjacent vertically-aligned headers varying, and a pair of reversely arranged blocks having co-operating longitudinally-inclined faces interposed between adjacent headers. 90

5. A crib retaining wall structure comprising a plurality of horizontal series of stretcher members, a plurality of horizontal series of alternate header members interlocked therewith, the distances between the opposed faces of the respective pairs of adjacent vertically-aligned members of one of said plurality of series varying, and a pair of reversely arranged blocks having cooperating inclined faces interposed between each 100 pair of said vertically adjacent members.

Signed by me this 28th day of October, 1926.

JOHN W. SHIMEK.
